UNITED STATES PATENT OFFICE.

CHARLES DAVID BONSALL, OF PITTSBURGH, PENNSYLVANIA, ASSIGNOR TO P. H. MURPHY COMPANY, OF NEW KENSINGTON, PENNSYLVANIA, A CORPORATION OF PENNSYLVANIA.

CAR ROOF.

Application filed June 21, 1926. Serial No. 117,331.

My invention relates principally to that type of flexible outside metal car roof wherein light gage roofing sheets are loosely connected along their adjacent margins by seam covers that permit relative movement of said roof sheets to a limited extent in accommodating themselves to the distortions of the car body.

The principal object of the present invention is an improved seam construction that will permit a limited sliding movement of the roof sheets transversely of said seam cover and will secure a sluing or oscillatory movement of said sheets in all positions of their sliding movement. Other objects are simplicity and cheapness of construction, compactness and economy of design and ease of assembly.

The invention consists principally in loosely connecting adjacent sheets by means of a seam cover having separate sliding and pivotal connections with said sheets. The invention further consists in the parts and in the combinations and arrangements of parts hereinafter described and claimed.

In the accompanying drawing which forms part of this specification and wherein like symbols refer to like parts wherever they occur,

Fig. 1 is a plan view of a flexible outside metal car roof embodying my invention;

Fig. 2 is a transverse section through one of the side seams on the line 2-2 in Fig. 1;

Fig. 3 is a transverse section through the roof at the eaves on the line 3-3 in Fig. 1;

Fig. 4 is a fragmentary plan view, showing the slidable and pivotal connections between the ridge seam cap and the roof sheets;

Fig. 5 is a vertical cross section through the ridge seam on the line 5-5 in Fig. 4; and

Fig. 6 is an enlarged detail section on the line 6-6 of Fig. 5.

Referring to the accompanying drawing, my invention is shown in connection with a car having wooden roof sheathing 7 supported on side plates 8 and a ridge pole 9. Metal roof sheets 10 are arranged on the roof sheathing 7 side by side in two rows on opposite sides of the ridge, the two rows of roof sheets being spaced apart at the ridge and the sheets in each row being spaced apart at their sides. The roof sheets on op-

posite sides of the ridge are arranged in 55 alignment transversely of the car; and mullions 11 are secured to the car in the spaces between the side margins of the seams. The mullions extend transversely of the car from eaves to eaves thereof and are of less width 60 than the spaces between the adjacent side margins of the sheets so as to permit a limited angular adjustment of the sheets between mullions.

The ridge and side margins of the roof 65 sheets are turned up and are thence bent inwardly and downwardly over the body portions of the sheets to form upstanding hook-shaped side and ridge seam flanges 12 and 13. The eaves ends of the roof sheets 70 are doubled under to form hook flanges 14 that loosely engage the doubled over hook flanges 15^a of angle flashing strips 15 secured to the eaves of the car, such arrangement serving to loosely retain the sheets on 75 the car at the eaves. The adjacent side seam flanges 12 of the sheets, together with the mullions 11 located therebetween, are preferably covered by inverted channel-shaped transverse or side seam covers or 80 caps 16 that extend from eaves to ridge of the car and rest on the said battens. The side seam covers 16 have inwardly and upwardly extending hook flanges 17 at their lower edges that interlock with the upstanding side seam flanges 12 of adjacent sheets. The eaves ends of the side seam covers are 85 loosely held in position by extensions 16^a that are turned down over the eaves ends of the mullions 11 and are thence turned under 90 the eaves corners of the roof sheets and hooked into the doubled back flanges 15^a of the eaves flashing strips 15.

Pressed metal ridge seam covers or caps 18 of substantially inverted channel-shaped 95 section straddle the spaced ridge flanges 13 of adjacent sheets and have outstanding base flanges 19 that rest on the body portions of said sheets inside the ridge and side seam flanges thereof. The adjacent ends of the ridge seam covers 18 and the transverse seam covers 16 are held in position on the car by means of the usual pan-shaped four-way corner caps 20 that are secured in position by means of vertical bolts 21, which also 100 secure the running board saddles (not shown) in position.

The base flanges 19 of the ridge seam

covers 18 are pressed upward midway of their length to form downwardly opening grooves 22 that extend transversely of said base flanges from side to side thereof. The 5 two grooves on the under sides of the two base flanges of each ridge cap are disposed in alignment transversely of the cap and are made wider at their ends than at their middle, preferably by bowing or curving their 10 opposing side walls away from each other from end to end of said grooves to form opposing convex surfaces 23 in the sides thereof. The ridge end portions of the body 15 portions of the sheets are provided midway of their side margins with upstanding ribs 24 that extend transversely of the seam covers and are straddled by the downwardly opening grooves 22 in the base flanges thereof.

20 The width of the narrow middle portions of the grooves in the base flanges of the seam covers corresponds to the width of the upstanding ribs 24 on the roof sheets, whereby said ribs have a snug fit in the said 25 grooves midway of their length and are normally spaced therefrom at their ends.

By the arrangement described, the ridge 30 ends of the sheets are properly centered between adjacent roof mullions by the rib and groove connections between the body portions of the roof sheets and the base flanges of the ridge seam covers; and said sheets are adapted to accommodate themselves automatically to the distortions of the car body 35 by sliding towards and away from each other along the transverse grooves in the base flanges of the ridge seam covers and by rocking upon the convex of said grooves.

An important advantage of the above 40 arrangement is that it secures a sluing, or pivotal movement of the sheets around points located in the region of the middle of their ridge ends in all positions of their sliding movement. Other advantages of the present 45 construction are the cheapness and simplicity of the construction of the roof sheets and ridge seam covers and the ease with which they may be assembled on the car.

The invention is not restricted to the precise shapes and arrangements of parts shown and described.

What I claim is:

1. A flexible car roof comprising roof sheets arranged on the car side by side, a 5 seam cover covering adjacent margins of said sheets, and means on the marginal portions of said seam covers cooperating with means on said roof sheets for permitting sliding movement of said roof sheets transversely of said seam covers and sluing movement of said roof sheets on said seam covers in substantially all positions of such sliding movement.

2. A flexible car roof comprising roof 45 sheets arranged on the car side by side, a

seam cover covering adjacent margins of said sheets, and means on each sheet cooperating with means on the adjacent marginal portion of said seam cover for permitting independent sliding movement of said roof sheets transversely of said seam cover and preventing bodily movement of said sheets longitudinally of said seam cover.

3. A flexible car roof comprising roof sheets arranged on the car side by side, a 75 seam cover covering adjacent margins of said sheets, and means on said sheets cooperating with means on the marginal portions of said seam cover for permitting independent sliding movement of said sheets 80 transversely of said seam cover, said cooperating means permitting independent sluing movement of said sheets around points located in the region of their adjacent margins and preventing bodily movement of said 85 sheets longitudinally of said seam cover.

4. A flexible car roof comprising roof sheets arranged on the car side by side, a seam cover covering adjacent margins of said sheets, and tongue and groove connections between the body portions of said 90 sheets and the marginal portions of said seam covers, said connections permitting independent sliding movement of said sheets transversely of said seam cover.

5. A flexible car roof comprising roof sheets arranged on the car side by side, a seam cover covering adjacent margins of said sheets, and tongue and groove connections between the body portions of said 100 sheets and the marginal portions of said seam covers, said connections permitting independent sliding movement of said sheets transversely of said seam cover, said tongue and groove connections also permitting independent sluing movement of said sheets 105 relative to said seam cover.

6. A flexible car roof comprising roof sheets arranged on the car side by side, a seam cover covering adjacent margins of 110 said sheets and having base flanges resting thereon, and sliding connections between the body portions of said roof sheets and the base flanges of said seam cover.

7. A flexible car roof comprising roof sheets arranged on the car side by side, and a seam cover covering adjacent marginal portions of said sheets, said sheets being provided with upstanding ribs adapted to engage transverse grooves provided therefor in 120 the marginal portions of said seam cover.

8. A flexible car roof comprising roof sheets arranged on the car side by side, and a seam cover covering adjacent marginal portions of said sheets, said sheets being provided with upstanding ribs adapted to engage transverse grooves provided therefor on the marginal portions of said seam cover, said grooves being wider at their ends than 125 at their middle.

9. A flexible car roof comprising roof sheets arranged on the car side by side and provided along their adjacent margins with upstanding seam flanges, and a seam cover straddling adjacent seam flanges of said sheets and having marginal base flanges resting on the body portions of said sheets, said roof sheet having tongue and groove connections with the marginal flanges of said seam cover that permit sliding movement of the sheets crosswise of said seam cover and sluing movement of said sheets in substantially all positions of their sliding movement.

10. A seam cover for a car roof, said seam

cover being of substantially inverted channel shaped section and having laterally extending base flanges that are provided with downwardly opening transverse grooves, said grooves being wider at their ends than at their middle.

11. A car roof sheet comprising a body portion having a flanged margin and a hollow elongated rib near the middle of and extending transverse to said margin and adapted to cooperate with a transverse groove in a seam cover.

Signed at New Kensington, Pa., this 16th day of June, 1926.

CHARLES DAVID BONSALL.
